PACKAGE FOR INFUSING MATERIAL

Christopher Luckhaupt, Jamaica, N. Y.

Application July 13, 1938, Serial No. 219,024

6 Claims. (Cl. 99—77.1)

My present invention relates to packages and more particularly to an improved package for the packaging and utilization of infusing material such as tea, coffee, and the like.

5 My invention is particularly adapted for the packaging of material for obtaining an infusion therefrom such as tea or coffee in large or small quantities such as may be adapted for individual use or restaurant use. In my present invention I 10 preferably utilize as the packaging material a material which is transparent or translucent and of such a character as to be partially or wholly insoluble in water of whatever temperature and of a character such as to impart no offensive taste 15 or odor to the infusion desired to be made. Such material preferably is made from regenerated cellulose and may be in the form of commercial so-called Cellophane. Such material in commercial form is imperforate and is obtainable 20 in a form that is insoluble in steam or water and does not contain any deleterious substance which would impart to the infusing water either taste or odor.

The material employed in making my improved 25 package, and of the character above stated, may be provided with puncturings of any desired shape and size, preferably relatively minute, and of such number per unit area depending in large 30 measure on the character of the material packaged therein.

Sheets or webs of such material are first punctured as above indicated and the resulting tabs or flaps of the material re-placed, preferably under pressure or otherwise to restore substantial 35 flatness of the sheet or web and substantial closure of the individual punctured locations.

Upon placing a package formed of my material, as aforesaid, in steeping water, as in the instance of tea or coffee or the like contained in 40 such package, such flaps or tabs afford entry of the water therethrough to form the infusion and the flow of the infusion from the interior of the package in return to the steeping water.

Accordingly, a feature of my invention is an 45 improved package of sheet material of regenerated cellulose provided with normally closed puncturing throughout its superficial area.

A feature of my invention, also, resides in an 50 improved package of sheet material of transparent or translucent regenerated cellulose or equivalent, insoluble in water and provided with normally closed puncturing throughout its superficial area and which puncturings are adapted to be opened upon immersion of the package in the steeping water or equivalent.

Other features of my invention will appear as the description of the invention progresses.

When thus packaged, the tea, coffee or the like contained therein, is precluded from sifting or other loss, the transparency or translucency of the material of the package affording visual inspection of the contents.

The substantially closed status of the packaging material also precludes loss of aroma of the contained material, and also substantially safe- 10 guards entry of atmospheric moisture or other exterior influence.

In the accompanying drawing,

Fig. 1 is a perspective view of an embodiment 15 of my invention utilizing transparent or translucent material of regenerated cellulose and in package or bag form;

Fig. 2 is a section taken on the line 2—2 of Fig. 1;

Fig. 3 is a perspective view of a sheet of re- 20 generated cellulose material from which the embodiment of my present invention illustrated in Figs. 1 and 2 may be made;

Fig. 4 is an enlarged section of a fragment of the material illustrated in Fig. 3 and showing a 25 manner of puncturing the sheet by tabs;

Fig. 5 is a view similar to Fig. 4 showing the respective tabs positioned back in substantial alignment with the sheet;

Fig. 6 is a view illustrating the movement of the tabs to open position under the influence of the steeping water;

Figs. 7, 8, and 9 illustrate in plan view, fragments of the cellulose sheet material and illustrating various types of puncturings, and

Fig. 10 is a perspective view of a completed package, bearing an improved form of tag encircling and retained by the package.

Referring to the drawing, and particularly to Figs. 1 and 2, 10 designates a package or sack 40 made from regenerated cellulose and which may be in the form either transparent or translucent and which package or sack is filled with material 41. Such material may be any material desired such as tea or coffee and from which an infusion 45 is to be made by steeping in preferably hot water.

The pouch or sack 10 is made from regenerated cellulose in sheet form and such a sheet is illustrated in Fig. 3 and designated by the reference numeral 12. The sheet of material 12 is mechanically provided with puncturings throughout its superficial area or throughout its designated superficial areas, such puncturings being designated by the reference numeral 13.

The puncturings designated 13 in Fig. 3 are

- illustrated in the making in Fig. 4 wherein a punch of substantially U-shape, as indicated in Fig. 7, cuts through the sheet 12, forming a tab 14, one end of which, as at the end 15, is integral with the sheet 12. Such tab therefore is positioned out by the punch or die and assumes the form shown in Fig. 4. After the making of the puncturings 13 the sheet 12 is preferably run through a calender or any other suitable device 10 and the tabs 14 are re-placed in the puncturings 13 so that the sheet 12 assumes a flat form as shown in Fig. 3, only the outline of the puncturings 13 being visible, the puncturings themselves being substantially closed by the tabs 14.
- 18 In Fig. 8 is shown a tab 16 of substantially V-shape with the end 17 thereof integrally formed with the sheet 12 and the puncturing made by such tab 16 and corresponding to the puncturing 13 will naturally have the form of tab 16.
- 20 In Fig. 9 is shown a fragment of a sheet of regenerated cellulose 12 in which a tab 18 has its end 19 integral with the sheet 12. The shape of the puncturing is naturally the shape of the tab 18.
- 25 Whatever the shape of the puncturing as the puncturing 13 or the shape of the corresponding tabs 14, 16 and 18, they will be during the making of the pouch or sack 10 shown in Figs. 1 and 2 closed by the respective tabs so that when a pouch or sack 10 is made from a sheet of regenerated cellulose 12 shown in Fig. 3, there is formed practically a pouch or sack which is imperforate. Being imperforate, there is no danger of any of the material as the material 11 sifting from the pouch or sack 10.

The pouch or sack 10 is made from the sheet 12 of regenerated cellulose by folding along the line 20 in Fig. 3 and running a line of stitching adjacent the edges 21 and 22 as indicated by the reference numeral 23 continuing such line of stitching by running the same adjacent to the edges 23 and 24 and then running the line of stitching adjacent the edges 25 and 26, the material utilized in stitching being extended in general stitched form to form an extension 27 to the end of which may be attached a tab.

Such tab is shown in position in Fig. 10 where the package or sack 10 has the general stitching material 27 attached to the tag 28. Such tag 50 may be of any material preferably regenerated cellulose having ends 29, a central zone 30 substantially equal to the width of the package or sack 10 and side zones 31 on either side of the central zone 20 whereby the central zone 30 may 55 rest on one face of the pouch or sack 10 and the side bands 31 on the opposite side of the said package.

When a filled package or sack 10, as shown in Fig. 10, is to be used, the user slips the tag 28 60 from off the sack or pouch and drops the sack or package with the infusing material 11 therein into the steeping water whereupon the water affects the material comprising the tabs 14 or 16 or 18 and they curl up and out of the position shown in Fig. 5 and into substantially 65 the position shown in Fig. 6, from an inspection of which it will be apparent that the puncturings 13 are now open permitting the steeping water to flow into and out of the pouch or sack 10 and 70 permitting the infusion to be made.

Because of the transparent or translucent character, and preferably transparent character of the material employed, the kind of material being held in the pouch or sack 10 is plainly visible 75 to the person desiring to either inspect or use the

same and the condition of the material to be infused may be determined at any stage of the infusion process. Being preferably of regenerated cellulose, the material 12 is insoluble in water regardless of the temperature of such water and 5 imparts no taste or odor to the infusion being made nor does it have any effect on the material packaged therein. The pouches may be made in any desired size and the puncturings made in such packaging material, while they permit the ready 10 flow of water and the infusion therethrough, will not be operated while in the dry state and thus sifting of the packaged material is prevented.

In the commercial production of the embodiments of my invention, a sheet or a continuous 15 web, as indicated in Fig. 3, of regenerated cellulose or other transparent or translucent cellulose film or equivalent material is treated to provide the desired punctured and non-punctured, i. e., imperforate, areas, by the employment of any 20 suitable means, such as a roll, having at its periphery over an area mutually spaced puncturing elements corresponding to the punctured area of the material, the remainder of the periphery of such roll being devoid of such puncturing elements and corresponding to the non-punctured area of the material. Such sheet or web may 25 then be passed through suitable smooth faced rolls to re-place the minute tongues or tabs within the individual punctured locations, to assume 30 a substantially flat status with relation to the adjacent non-punctured, i. e. imperforate portions of the sheet or web. Desirably the sheet or web is passed through such sets of puncturing and replacing rolls under tension in the direction 35 of the greater tensile strength of the material of the sheet or web, thus utilizing the resiliency of the material to more effectively puncture the material and more effectively upon release from tension to restore the minute flaps or tabs within 40 the individual punctured locations. In such operation, the puncturing or perforating roll or rolls may be positively driven at substantially the same surface speed as the travel of the sheet or web.

Whereas I have described my invention by reference to specific forms thereof, it will be understood that many changes and modifications may be made without departing from the spirit of the invention.

I claim:

1. An improved package for infusing material composed of regenerated cellulose in sheet form and provided with puncturings normally substantially closed by tabs forced from the material to form the respective puncturings and with said 55 tabs normally lying in original position to substantially close the individual puncturings, and said tabs moved to open position by the action of hot extracting medium.

2. An improved package for infusing material, such as beverage material, made from a sheet of regenerated cellulose material in sack form and provided with puncturings through designated superficial area and normally substantially closed by tabs formed integral with the sheet of regenerated cellulose material, and said tabs opening by the action of hot extracting medium.

3. An improved package for infusing material, such as beverage material, made from a sheet of regenerated cellulose material in sack form and 70 provided with puncturings through designated superficial area and normally substantially closed by a tab formed integral with the sheet of regenerated cellulose material and with the package closed by sewings of fibrous material, said tabs 75

opening by the action of hot extracting medium.

4. An improved package for infusing material, such as beverage material, made from a sheet of regenerated cellulose material in sack form and provided with puncturings through designated superficial area and normally substantially closed by tabs formed integral with the sheet of regenerated cellulose material, said tabs moving to open position by the action of hot extracting medium, and with the package closed by sewings of fibrous material, and with the ends of the fibrous material extending beyond the package, and a tag attached to said end.

5. An improved package for packing infusing material, such as beverage material comprising cellulose material provided with puncturings,

the tabs of such puncturings being normally substantially closed, the material possessing the property upon wetting to effect movement of the tabs from their normally substantially closed positions.

6. An improved package for infusing material, said package made from regenerated cellulose in sheet form and provided with puncturings of any desired number and size throughout a designated superficial area and with the puncturings normally substantially closed by tabs forced from the material to form the respective puncturings, and said tabs moved to open position by the action of hot extracting medium.
